J. FLEISCHMAN

TELEPHONE RECEIVER APPARATUS

Filed June 24, 1922

UNITED STATES PATENT OFFICE.

JOSEPH FLEISCHMAN, OF NEW YORK, N. Y.

TELEPHONE RECEIVER APPARATUS.

Application filed June 24, 1922. Serial No. 570,745.

To all whom it may concern:

Be it known that I, JOSEPH FLEISCHMAN, a citizen of the United States, and resident of New York city, in the county of New York and State of New York, have invented certain new and useful Improvements in Telephone-Receiver Apparatus, of which the following is a specification.

My present invention relates to distributing telephone receivers and has its preferred application to radio receiving sets.

It is an object of the invention to provide an inexpensive and serviceable receiving set which shall accurately deliver the message or performance to be heard concurrently by a plurality of persons without incurring the distortions commonly associated with the use of amplifying horns.

Another object is to provide a radio receiving set which shall render possible the listening in by a multiplicity of persons without the need for more than one telephone diaphragm.

Another object is to provide a distributing receiver unit susceptible of use with a single ordinary watch-type telephone receiver for faithful and efficient delivery to a plurality of listeners.

Other objects will be in part obvious and in part pointed out hereinafter.

In the accompanying drawings in which is shown one or more of various possible embodiments of the several features of this invention,

Fig. 1 is a transverse sectional view of a preferred form of distributing receiver,

Fig. 2 is a plan view thereof,

Fig. 3 is a detail sectional view on an enlarged scale taken along the line 3—3 of Fig. 1,

Fig. 4 is a transverse sectional view on a smaller scale of a modification,

Fig. 5 is a transverse fragmentary view of a further modification, and

Fig. 6 is a diagrammatic plan view indicating a preferred application of the receiver.

Referring now to the drawings, I have shown in Figs. 1, 2 and 3 a distributing receiver comprising a base block 1 of generally cylindrical form having preferably a felt support 2. The telephone receiver proper is mounted upon the upper end of the block. This receiver comprises the usual watch-type casing 3 enclosing the usual electro-magnets 4 and has the usual threads 5 at

the exterior thereof for the ear plate. The upper end of the support block is tapped as at 6 and the casing 3 is threaded thereinto, instead of into an earplate. The telephone diaphragm 7 preferably rests upon a peripheral ledge 8 formed on an annular hard rubber plate 9 fitting snugly into an annular depression 10 in the support block below the tapped portion 6, the receiver casing when threaded home preferably clamping the diaphragm 7 against the peripheral ledge 8 and clamping the disk 9 against the support block 1, a felt washer 11 being preferably interposed to render the connection sound tight. The lower surface of the disk 9 is preferably dished as at 12 about the central aperture 13 substantially in the manner of the ordinary receiver earplate and may, if desired, be formed from the ordinary earplate of a telephone receiver by removing the peripheral portion thereof in the manner which will be obvious.

It will be seen that the small air chamber 14 below the diaphragm and disk 9 constitutes a sound chamber from which the vibrations originating in the diaphragm, are to be passed on to the various listeners. In a preferred form the support block has a small cylindrical depression or well 15 below the sound chamber and communicates with preferably four radial ducts 16 through the distributing block in which fit nipples 17, any one or more of which may be connected to sound conveying tubes 18 preferably binaurals, the outer ends of which may carry the usual ear pieces 19 for insertion, one into each auditory orifice. To distribute the sonorous energy equally and symmetrically to the various outlets, I prefer to fit a spider 20 into the cylindrical depression 15 having arms 21 frictionally fitted against the wall portions 22 of the support block between the successive ducts 16, thus forming a distributing chamber. Closure caps 23 are preferably provided with rubber gaskets 24 to form air-tight closures for the outer ends of the nipples 17 for those tubes not in use, when less than the maximum number of persons within the range of the apparatus are listening.

The sound and distributing chambers are of such small volume as to be resonant to a pitch above the range of audibility, as distinguished from a sound chamber of materially larger dimensions that will resonate to

some one definite pitch and may correspondingly distort the sound.

In Fig. 4 is shown an alternative form of the invention in which the base block has a cylindrical distributing chamber 25, nipples 26 in ducts 27 extending radially through the wall 28 for connection of the sound tubes 18. The diameter of this chamber is preferably not more than 2.5 inches 10 to avoid resonating to a high pitch within the range of audibility.

In Fig. 5 is shown another alternative form in which the distributing chamber 29 is of inverted generally conical form, ducts 30 radiating from near the tip 31 thereof for connection of the nipples 32. The vibrations from the diaphragm, it will be seen generate corresponding vibrations in the chamber 29 which pass toward the tip 31 thereof, but are relieved through the radiating ducts 30 and nipples 32 and pass on to the binaurals.

Except as heretofore described, the embodiments shown in Figs. 4 and 5 are preferably identical with that of Figs. 1 and 3.

In use, the multiple distributor may be placed upon a table, the telephone wires 33 and 34 being connected to the familiar telephone terminals of the radio set and each 30 listener will take a pair of binaurals, caps 23 being used to close any nipples out of use.

In a preferred embodiment, the multiple receiver may be mounted upon or within a radio receiving set of generally conventional external appearance. Fig. 6 shows a familiar form of such set including a box 35 having a panel 36 behind which is mounted a detector tube 37 visible through aperture 38 and adjustable by knob 38', operating knobs, one of which is shown at 39, serving for effecting the usual tuning adjustments, the terminal binding posts for the ground and for the antenna being shown at 40 and 41. In my preferred form of set, 45 the usual telephone terminals would be omitted, and in lieu thereof, there would be sockets as at 42 for attachment of binaurals 18, these sockets being connected by conduits 43 to the multiple radio receiver R of 50 any of the constructions previously described, mounted in any convenient manner preferably within the box and to the rear of the panel. Thus, the telephone would be concealed and the binaurals merely would be 55 handled and used by the listeners. Of course, caps such as at 44 would be furnished to close any sockets not in use when the number of listeners is less than the maximum permitted by the range of the device.

60 Thus, it will be seen that I have provided a multiple telephone receiver of general application, but more particularly useful for radio receiving sets. The device utilizes but a single telephone diaphragm 65 and thus dispenses with the need for a tele-

phone or a pair of telephones for each listener. It will be noted that the diaphragm vibrations are transmitted to the multiplicity of listeners without the distortions commonly accompanying the use of sound 70 amplifiers.

It will thus be seen that there is herein described apparatus in which the several features of this invention are embodied, and which apparatus in its action attains the 75 various objects of the invention and is well suited to meet the requirements of practical use.

As many changes could be made in the above construction, and many apparently 80 widely different embodiments of this invention could be made without departing from the scope thereof, it is intended that all matter contained in the above description or shown in the accompanying drawings shall 85 be interpreted as illustrative and not in a limiting sense.

Having thus described my invention, what I claim as new and desire to secure by Letters-Patent of the United States is:—

1. In a distributing telephone receiver, in combination, a base block, an annular disk fitting into a corresponding depression in said block, and having a peripheral ledge, a diaphragm resting upon said ledge, an electromagnet casing threaded into said base block and engaging the periphery of said diaphragm to clamp the same in position, and ducts through said base block in communication with said depression to distribute the sonorous vibrations generated by the diaphragm.

2. In a distributing telephone receiver, in combination, a base block, an insulating annulus resting in the upper end of said block and dished at the surface thereof facing said block and having a peripheral ledge at the other side thereof, a diaphragm resting upon said ledge, and a casing for the electromagnets of said telephone, said casing having a periphery threaded into the end of the base block to clamp said diaphragm in position, and taps through said block in back of said annulus to distribute the sound uniformly.

3. In a distributing telephone receiver, in combination, a distributing base block having a plurality of ducts therethrough communicating with a central distributing cavity, an annular plate resting in a corresponding depression in the upper end of said base block and countersunk about its inner periphery at the lower surface thereof and having a ledge about its outer periphery at the upper surface thereof, the upper end of said base block being interiorly threaded to accommodate the threaded periphery of the electromagnet casing of an ordinary telephone, whereby upon threading said casing into the upper end of said base block, the diaphragm will be clamped into effective position.

sition to set the air in said chamber into vibration and to distribute the sound therefrom uniformly through said ducts.

4. In a distributing telephone receiver, in combination, a base block having a cylindrical chamber therein of dimensions to resonate to a pitch beyond the range of audibility, radial outlet ducts in said block communicating with said chamber, and a telephone receiver threaded into said block and having a diaphragm across said chamber.

5. In a distributing telephone receiver, in combination, a base block having a cylindrical chamber, in the upper end thereof, radial outlet ducts communicating through the lateral wall thereof, a telephone receiver having an earplate annulus resting upon a flange near the upper end of said base block, a diaphragm resting upon said annulus, and an electromagnet containing casing threaded into the upper end of said block to clamp the periphery of said diaphragm in position against said annulus.

6. In a distributing telephone receiver, in combination, a base block having a small central distributing chamber generally coni-

cal in form, radial outlets extending through said block and communicating with said chamber, an ear plate fitting into a corresponding cylindrical depression in said block 30 and above said chamber and having a peripheral ledge, a diaphragm resting upon said ledge and a telephone receiver casing member threaded at its periphery into said block to clamp said diaphragm against said 35 ear plate and to clamp said ear plate against said block for establishing a sound tight communication between said diaphragm and said distributing chamber.

7. In a distributing telephone receiver, in combination, a base block having a cylindrical axial well therein, ducts radiating from said well, a partition spider construction fitting into said well and frictionally held 40 against adjoining wall portions between said 45 ducts, and a telephone receiver unit having a diaphragm connected to communicate its vibrations to said well.

Signed at New York in the county of New York and State of New York, this 22nd day 50 of June, 1922.

JOSEPH FLEISCHMAN.
